(No Model.)

L. D. BLISS.
TELEGRAPH KEY.

No. 530,082.

Patented Dec. 4, 1894.

UNITED STATES PATENT OFFICE.

LOUIS D. BLISS, OF WASHINGTON, DISTRICT OF COLUMBIA, ASSIGNOR TO
CHARLES W. NEEDHAM, OF SAME PLACE.

TELEGRAPH-KEY.

SPECIFICATION forming part of Letters Patent No. 530,082, dated December 4, 1894.

Application filed March 7, 1894. Serial No. 502,760. (No model.)

To all whom it may concern:

Be it known that I, LOUIS D. BLISS, a citizen of the United States, residing at Washington, in the District of Columbia, have invented certain new and useful Improvements in Telegraph-Keys, of which the following is a specification.

In the use of the ordinary system of telegraphy, especially where what is known as the Morse key and sounder is used in transmitting and receiving, it is a well-known objection that unauthorized persons can read and understand the message being transmitted and received by listening to the sounds made by the key, or by the sounder or receiving device, and this is especially true where a large number of instruments are operated together in the same room, for instance, and they are adjusted and supplied with sufficient battery-power to make distinct and loud sounding signals.

One of the objects of my present invention is to provide means whereby an ordinary telegraphic message may be transmitted and received by authorized persons, but which cannot be received in a manner to be clearly understood surreptitiously read and understood by unauthorized persons. In other words, I provide a practically silent transmitter or key and a receiver which while the sounds are distinct and sharp and of a character to be easily read and understood when the instrument is in the proper position, they are of such slight volume that they cannot be heard or understood by unauthorized persons.

In my prior application, Serial No. 487,965, filed October 12, 1893, I have illustrated and described a receiving instrument specially adapted for this class of work, and capable of overcoming the objections stated, as far as the receiving end of the line is concerned, and the object of my present invention is to provide a transmitting instrument or key which, while it shall conform as nearly as may be to the ordinary transmitter key in use, shall perform its functions practically noiselessly, so that the signals sent cannot be heard except by the proper person connected with the line.

Further, my invention includes the combination

of such a noiseless transmitter and receiving instrument, and as such an instrument is not adapted to be used to call an operator at a station when adjusted for this purpose, my invention further includes some sort of an arrangement whereby the attention of the operator may be called to the fact that a signal is to be transmitted.

With these general statements as to the purposes and objects of my invention, it may be considered to consist in a noiseless transmitter key, and the combination with said key of a suitable receiver and signal device, substantially as hereinafter more particularly pointed out.

Referring to the accompanying drawings: Figure 1, is a side view of a desk or table, showing an arrangement of devices embodying my invention. Fig. 2, is a plan view of the same; and Fig. 3, is a longitudinal, vertical section through the noiseless key, showing the preferred construction thereof.

The receiving table or desk is shown as comprising a platform A, and an upright A', on which the various instruments are mounted, but this of course, is not essential to my invention, being shown only as a convenient embodiment or arrangement of the parts, and of course can be varied to suit the requirements of any particular case. Supported on this platform is a noiseless key B, and this is connected with the electric circuit in the usual way, by conductors passing through the base of the platform, and arranged also on the platform are the binding-posts c, to which the receiver C, is attached by means of a flexible cord C', or otherwise, and also mounted on the upright is a signal device D, which is also arranged to be operated by the transmitting key, in the manner more particularly pointed out hereinafter.

The transmitter key B, embraces the usual base-piece B', having ears or standards B², in which is mounted the key-lever B³, which is under the bias of a spring, as B⁴, and is provided with the usual knob or handle B⁵, and an adjustable back-stop B⁶. In other words, so far the key is shown in the conventional form, and while I have illustrated one of the

most common forms, of course, any other well-known or equivalent form may be used, to suit the pleasure of the operator. It is usual to provide the back-stop with a metallic or other rest-piece B', which will produce a sound when the back-stop comes in contact therewith, but to avoid this objection and to aid in making the key noiseless, I provide a back-rest B', of some non-resonant or non-sound-producing material, such for instance, as a block of rubber, and secure the same to the base B', in any desirable way. It is also well known that it is considered good practice to provide the key with metallic contacts, which are usually made of platinum, one being supported upon the key-lever, and the other upon the base, and the depressing of the key-lever to bring these contacts together to control the electric current and produce a signal on the line, produces a loud and distinct noise, so that the signals can be easily read and understood by unauthorized persons in the vicinity of the transmitter. In order to avoid this, I provide the key-lever with a contact b, which may be of platinum or similar material and provide another contact b', which may be of the same material, and so support the contact, that when the two contacts are brought together to control the electric circuit, practically no noise shall be made which would enable an unauthorized person to ascertain the nature of the message being sent. While various means of supporting this contact may be used, I have found it desirable to have it maintained with considerable rigidity or positiveness in its fixed or normal position, but still be capable of yielding perhaps to a slight extent, and anyway being supported by a non-resonant or sound-transmitting support. I have found rubber to be one of the best materials, and the contact may be supported on a block or mass of rubber and connected directly with the line wire e, but as a refined and more satisfactory means of supporting the contact, I connect it to a flexible conductor E, and coil the conductor between layers of a rubber sheet or fabric f. Thus, I have shown the contact b', as connected to the end of the conductor e, and the conductor is wound preferably in a spiral relation between the superposed layers of the rubber fabric or sheet f, and in this way not only does the rubber tend to maintain the contact in proper position, but the coil of wire acts as a coiled spring to aid in supporting the contact, and as no two metallic parts of the contact or conductor are adjacent each other (a mass or thickness of rubber intervening between all parts) practically no sound or noise will be made when the key is manipulated in the usual way. Not only does this permit the key to operate as a noiseless key, but the somewhat elastic contacts make the manipulation of the key less tiresome to the operator.

While of course, any receiving apparatus

I can be operated in the usual way with a key of this character, in order to further carry out the main object of my invention, I preferably use a receiver C, which can be of a reduced size, and in which while the sounds or signals shall be sharp, clear and distinct, so that they can be readily heard when the receiver is applied to the ear of the receiving operator, they cannot be understood by unauthorized persons, and I do not deem it necessary herein to describe the specific construction of such a device, as it is fully set forth in my former application, and as broadly considered, an ordinary magneto-telephone receiver may be used in its place.

As before intimated, it is desirable to be able to call an operator at any particular station to let him know that communication is desired, and as the receiver does not ordinarily give out a sufficient sound to attract the attention of the operator, some means has to be provided for calling him. It is possible to adjust the receiver C, so that the signals can be heard at a considerable distance from the instrument, and thereby attract the attention of the operator, but as this would require that the receiver should be in the transmitting circuit all the time, it would destroy to a great extent the purposes and objects of my invention, as unauthorized persons could listen and obtain the messages passing through the instrument destined for other stations. In order to avoid all these difficulties, I provide a calling apparatus D, and this is shown as comprising a magnet D', which is arranged in the electric circuit, but which is so wound that it acts as a sluggish magnet, and will not be magnetized by the ordinary currents produced in sending the usual signals, and so that its armature D², would not be fully attracted unless there was an unusual prolongation of the continuous current, or dwell in the operation of the transmitting key. As, however, such a magnet would offer more or less objectionable resistance to the circuit, in preference to making a sluggish magnet, I provide means to retard the movements of the armature, and I have shown a dash-pot D³ in which there is a piston D⁴, connected by a pitman D⁵, to the armature D², and there is a check valve D⁶, controlling the opening d, and the retracting spring D⁷, is so adjusted as to normally hold the piston in the uppermost part of the cylinder, or adjacent to the valve. When the coils of the magnet D' are energized, the tendency, of course, is first to attract the armature lever D², and its armature, but it being at this time at the greatest distance from the magnet, not only is the attraction of magnet D' less, but the dash-pot tends to prevent the rapid movement of the armature lever until after a relatively considerable time, longer than any ordinary signal to be transmitted by the key, and when of course, the circuit is broken, the spring D⁷, will retract the armature lever, its piston or check valve D⁶, open-

ing easily to permit the piston to rise in the cylinder. It will thus be seen that only when there is a prolonged closure of the circuit made at the transmitting key, so that the 5 magnetism of the magnet D', will be maintained a considerable period of time, will the alarm or signal device be operated, and it will be observed that the armature lever itself will impinge violently upon the cores of 10 the magnet, as soon as the piston is released, or practically released from the cylinder and make a sufficient sound to act as a signal, but in some cases it is preferable to use a bell or gong G, and attach to the armature lever a 15 hammer H, which will impinge upon the gong and give a distinct signal. It will thus be seen that with this arrangement of circuits, not only can a message be noiselessly transmitted by manipulating the noiseless key, but 20 it can be received so that it will be unintelligible except to the proper person, and the danger of surreptitiously obtaining knowledge of the message sent is avoided. Moreover, the signal circuit is practically inop- 25 erative in the ordinary transmission of the message, but by holding the circuit closed at the transmitter, a signal may be given to attract the attention of the operator at any desired station, and it will further be observed 30 that when once the piston is withdrawn or practically so, from the cylinder, a series of 35 short signals or calls can be given before the piston has time to return to its normal position. It will thus be apparent that these instruments co-operate with each other in producing a complete, noiseless, or as it may be termed, secret system of electric transmission and it can be readily applied to any existing lines, without material change, by sim- 40 plly substituting my noiseless key and a practically noiseless sounder or relay.

I have found that the receiver will operate satisfactorily without the interposition of a local battery at the receiving station, and it 45 can be placed directly in line in place of the ordinary relay, and the magnet of the signal device can also be included between the terminals of the main line.

Having thus described my invention and 50 pointed out the preferred embodiments thereof, it will be evident that I do not limit myself necessarily to the precise construction and arrangement of parts herein set forth, as they may be varied in detail by those skilled

in the art, without departing from the general principles of my invention. 55

What I claim is—

1. A noiseless transmitting key, comprising a non-resonant support, and a contact mounted on the support, substantially as described. 60

2. A noiseless transmitting key, comprising a non-resonant contact-support, a contact mounted on the support, and a non-resonant contact-stop, substantially as described. 65

3. A noiseless transmitting key, provided with a non-resonant contact support, comprising superposed layers of fabric with a conductor interposed between the layers, and a contact mounted on the support, substantially 70 as described.

4. A noiseless transmitting key, comprising a non-resonant contact support consisting of superposed layers of fabric, a conductor spirally arranged between the superposed layers, 75 and a contact mounted on the support connected to the conductor, substantially as described.

5. The combination with an electric circuit, of a noiseless transmitting key comprising a 80 non-resonant support and a contact mounted on the support, and a practically noiseless receiver, both the key and receiver being connected in said electric circuit, substantially as described. 85

6. The combination with an electric circuit, of a noiseless transmitting key, comprising a non-resonant contact support and a contact mounted on the support, a non-resonant receiver included in the circuit, and a retard- 90 ing signal device also included in the circuit, substantially as described.

7. The combination with an electric circuit, of a noiseless transmitting key, comprising a non-resonant contact support and a contact 95 mounted on the support, a non-resonant receiver included in the circuit, a magnet also included in the circuit, an armature for the magnet, and retarding devices connected to the armature, substantially as described. 100

In testimony whereof I have signed my name to this specification in the presence of two subscribing witnesses.
